CLAIM

We claim the ornamental design for a shower device, as shown and described.

DESCRIPTION

FIG. 1 is a front perspective view of a shower device, such as a shower head.

FIG. 2 is a rear perspective view of the shower device shown in FIG. 1.

FIG. 3 is a front view of the shower device shown in FIG. 1. FIG. 4 is a rear view of the shower device shown in FIG. 1. FIG. 5 is a left side view of the shower device shown in FIG. 1, the right side view being substantially a mirror image thereof.

FIG. 6 is a top view of the shower device shown in FIG. 1, the bottom view being substantially a mirror image thereof; and, FIG. 7 is a front perspective cross-sectional view of the shower device shown in FIG. 1 to illustrate contours of the shower device.

One or more side and/or bottom views of a shower device are mirror images of another view and, therefore, have been omitted.

The cross-sectional view is provided to illustrate contours of the shower device. The interior of the cross-sectional view forms no part of the claimed design.

Any broken line showing of the environment or a boundary line is for illustrative purposes only and forms no part of the claimed design.
